J. M. LEA

MANUFACTURE OF METALLIC BELLows

Filed Nov. 19, 1925

UNITED STATES PATENT OFFICE.

JOHN M. LEA, OF DETROIT, MICHIGAN.

MANUFACTURE OF METALLIC BELLOWS.

Application filed November 19, 1925. Serial No. 70,115.

The invention relates to the making of metallic articles built up from a plurality of sections and, while in some respects of more general application, is of especial utility in connection with, and will be herein described as applied to, the making of resilient bellows formed from a plurality of sections of sheet metal and adapted for use in pumps, thermostats and other mechanisms in which an expandible metallic chamber is required.

The principal object of the invention is to provide improved means for the manufacture of articles of the character mentioned by assembly of suitably formed metal sections, and, while retaining the sections in assembled relation, applying solder, or the like, to join the sections and produce a unitary structure.

Other objects and advantages will appear from the following description taken in connection with the accompanying drawings, in which—

Fig. 1 is a plan view of a structure adapted for use in applying solder to a set of metal sections,

Fig. 2 is an end elevation of the same,

Figs. 3 and 4 are, respectively, a side elevation, partly in section, and an end elevation of a clamp adapted to hold a set of sections in assembled relation while being soldered,

Fig. 5 is a view on an enlarged scale showing a set of sections properly positioned relatively to the solder-applying devices preliminary to the operation of soldering, and

Figs. 6, 7 and 8 are plan views, respectively, of an end plate and two forms of intermediate plates employed in the construction of the bellows.

Referring to the drawings, the structure with which the invention is concerned is shown as a metallic bellows comprising an end plate 10, intermediate plates or rings 11, 12, and a base plate 13. The end plate may be provided with a central opening 14 adapted for the attachment of an actuating or supporting device and is formed with a downwardly extending peripheral flange 15. The intermediate plate or ring 11 is provided at its outer edge with an upwardly extending flange 16 and at its inner edge with a downwardly extending flange 17. The

inner edge of the ring 12 is also upwardly flanged, as at 18, and the outer edge downwardly flanged, as at 19. The base plate 13 is centrally apertured with an upwardly extending flange 29 around the aperture and may have one or more annular stiffening and locating ribs 20'. The diameter of the central aperture in the plate 13 is the same as that of the aperture through one of the rings 12 and is slightly greater than the diameter of the aperture through one of the rings 11. The diameter of plate 10 and of ring 12 is slightly less than that of ring 11. These differences are made just sufficient to enable flange 15 or flange 19 to seat and fit closely within flange 16 and flange 17 to seat over flange 18 or 20. Thus, as will be clear from Fig. 3, the plates and rings, which may be stamped or otherwise formed from sheet metal possessing the desired resilience, may be assembled to constitute a bellows member having any required number of folds or convolutions. It is only necessary then to stamp or otherwise form from sheet metal possessing the desired resilience, may be assembled to constitute a bellows member having any required number of folds or convolutions. It is only necessary then to 55

secure together, as by soldering, the respective pairs of nested flanges to produce a bellows member having a high degree of flexibility and the walls of which are of sheet metal of substantially uniform thickness. 60

After having selected and stacked together the plates and rings necessary to form a bellows member of the desired number of folds the assembly is then mounted in a clamp adapted to retain the elements in proper position during the soldering operation. A clamp suitable for this purpose, illustrated in Figs. 3 and 4, comprises a base or body portion 25 and two arms 26, 27. The body portion is provided with a bore 28 to permit the clamp to be mounted on a soldering apparatus hereinafter described. The arm 27 is centrally apertured at 29 and within the aperture is rotatably mounted a sleeve 30 adapted to support upon its inner face of the base 13 of a set of elements for a bellows member. The sleeve 30 may be retained in the aperture 29 in any suitable manner, as by a flange 31 turned over the outer face of arm 27. An antifriction bearing is preferably provided between the sleeve 30 and the arm 27, as by means of balls 32 mounted between the opposed faces of the sleeve and the arm. The central bore 33 of the sleeve is of 65

80

85

90

95

100

sufficient diameter to permit the introduction of a soldering tool as later explained.

The arm 26 is provided with a bearing 34 adapted to receive and support a plunger 35 axially aligned with the sleeve 30. A retaining device or catch 36 is arranged to engage with the plunger to retain the same at the inner limit of its movement, which limit may be determined by a collar 37 adjustably mounted upon the plunger and adapted to engage the outer face of the arm 26. At its inner end the plunger is provided with means, as teeth 38, for engagement with the top or end plate of a set of bellows elements, and a central finger 39 is preferably provided to fit the aperture 14 and thereby assist in centering the set of elements.

In practice, the set of assembled sections or elements to constitute a bellows member is placed upon the sleeve 30, being centered relatively thereto in any suitable manner, as by the provision of the concentric ridge 30' on the face of the sleeve over which the rib 20' may seat, then the plunger 35 is pushed inwardly to engage the end plate 10. The space between the sleeve and plunger will be so adjusted that the bellows assembly will be subjected to a slight pressure so as to retain the sections firmly in engagement and 30 gauge the length of the bellows.

The apparatus for applying solder to the joints of the bellows assembly comprise a base or frame 40 upon which are rotatably mounted two soldering tools or rollers 41, 42. The roller 41, as shown on an enlarged scale in Fig. 5, is provided at its extremity with a plurality of circumferential grooves 43 spaced apart the same distance as the inner joints of the bellows assembly when supported in the clamp above described. These grooves are curved in cross section, as shown, to the extent necessary to fit over the flanges 17, 18, or 17, 19, in the bellows assembly when moved into engagement therewith so as to apply solder thereto and at the same time exert a slight pressure tending to force the flanges together axially.

The tool 42, as shown in detail in Fig. 5, is constituted of a plurality of separate rollers 44 corresponding in number to the number of outer joints in the bellows assembly and mounted somewhat loosely upon a spindle 45, being spaced apart by washers 46. The rollers are peripherally grooved, the grooves being shaped similarly to the grooves 43 in the roller 41. The portion 43' of groove 43, for engagement with flange 17, is recessed somewhat more deeply than the remaining portion of the groove so that the 60 deeper part of the groove may provide a seat for the flange 17 while the higher part will engage the flange 18 or 20. Similarly a portion 44' of the groove 44 is deeper than the remaining portion of the groove to provide a seat for flange 16. By reason of this

formation the rollers engage both plates on each side of each joint, which action is necessary in order to insure the flowing of the solder uniformly into the joint.

The series of rollers 44 are rotatably supported, as by the adjustable bearing screws 47, in a reciprocating frame comprising bars 48 mounted to slide in standards 49, 50. The bars are connected at their rear ends by a cross piece 51 against which acts a lever 52 adapted to be actuated by a treadle 53 or other suitable means to move the roller tool 42 toward the roller 41. Springs 54 serve to move the tool 42 in the other direction, the extent of movement under the influence of the lever being determined by the adjustable stop 55, on cross bar 51, engageable with standard 50, and the return movement being limited by stop 56 on the bars 48, engageable with standard 49.

The roller 41 is formed integrally with a shaft 60 of sufficient size and of suitable material to conduct the necessary heat to the soldering roll. The shaft is suitably supported for rotation and, if desired, for reciprocation, as in bearings 61, and may be rotated by any desired means, as by crank 62. Heat radiating or insulating means 63 may be arranged to retard communication of heat to the crank. Heat may be supplied to the tool 42 and the shaft 60, respectively, by burners 64, 65, supplied with gas from pipe 66.

To provide for the support of the bellows assembly in proper relation to the soldering tools just described, a rod 70 is mounted in a horizontal position upon a standard 71. This standard also supports a second rod 72 slightly offset vertically from the rod 70 but parallel thereto. The rod 70 is of a size to fit slidably within the bore 28 of the bellows clamp, while the rod 72 serves as a guide for properly positioning the clamp relatively to the roller 41.

In operation, the clamp with a bellows assembly positioned thereon, a suitable soldering flux having been applied to the bellows elements, is placed upon the rod 70 and brought against the guide 72 by swinging the clamp about the axis of rod 70. If desired, the soldering roll 41 may, at this time, be in a retracted position if the supporting shaft is slidably mounted to permit the withdrawal of the tool from the soldering position. However, this is unnecessary if the clamp be properly held against guide 72. An adjustable stop 71' may be provided to limit the endwise movement of the clamp. After the bellows clamp has been properly located and the roller 41 is positioned in the interior of the bellows assembly as shown in Fig. 5, solder having been applied, of course, to the roller before entering it into the bellows, and also to the tool 42, the treadle 53 may be operated to move the tool

42 toward the roller 41. This movement first brings the rollers 44 into engagement with the outer joints of the bellows, and, as the movement continues, swings the soldering clamp about the rod 70 and thus brings the inner joints into engagement with the grooves of roller 41, the adjustment of the parts being such that a slight pressure will be exerted upon the joints by their engagement with the several grooves. The roller 41 is now rotated a few revolutions. This movement is communicated to the bellows assembly by reason of the frictional engagement of the latter with the roller, and rotation is likewise imparted to the roller 44, the loose mounting of the latter permitting them to accommodate themselves to any slight irregularity of the bellows sections. The joints will thus be lightly pressed together while solder is being applied by the roller tools and the joining of both the interior and exterior joints will be very quickly accomplished. Furthermore, the solder will be very uniformly and completely applied to the entire periphery of each joint, since every point is brought once, or several times if desired, into contact with the soldering irons thereby attaining an even and proper temperature. The contact also extends to both members uniformly on both sides of the joint, without which a satisfactory soldering cannot be effected.

From inspection of Fig. 5 it will be noted that the outer flanges 16 on the external joints of the bellows are directed upwardly or away from the base 13, while the innermost flanges 17 on the internal joints are directed downwardly or away from the top 10. As a result of this arrangement the external joints are exposed to view from the upper side and the internal joints from the lower side through the opening in the base plate, thus facilitating inspection.

The roller 41 is formed in a single body integral with its supporting shaft 60 since it is necessary to heat the internal soldering tool by conduction from the heated shaft 60. The external tool 42, on the other hand, may be heated directly, as by burner 64, and therefore may be made in sections non-rigidly connected, thus enabling it to accommodate itself in position and rate of rotation to the joints with which it contacts.

While I have herein described a specific embodiment of the invention in both method and apparatus it will be understood that various changes in details may be made by one skilled in the art without departing from the spirit and scope of the invention and therefore I do not wish to be restricted to the specific features herein set forth except as required by the language of the appended claims in view of the prior art.

I claim:

1. The process of forming a bellows com-

prising assembling a plurality of sheet metal sections so fitted together as to present internal and external joints, maintaining said assembled sections under pressure, and applying solder simultaneously to the internal 70 and external joints by rotating the assembly in contact with rotary soldering tools.

2. The process of making a metallic bellows member, comprising the provision of sheet metal rings having flanges upon their 75 inner and outer peripheries, assembling such rings with the flanges of one ring in engagement with corresponding flanges of adjacent rings, and applying solder simultaneously to the inner and outer mating 80 flanges.

3. The process of making a metallic bellows member comprising assembling a plurality of sheet metal sections so fitted together as to present internal and external 85 annular peripheral joints, positioning said assembly between two roller soldering tools, and rotating one of said tools, thereby imparting rotation to the assembly and the other tool. 90

4. Soldering apparatus comprising means for supporting a work-piece having inner and outer joints, a soldering roller adapted to be positioned within said work-piece in engagement with said inner joints, a second soldering roller adapted to be positioned in engagement with said outer joints, and means for causing relative rotation of each of said rollers and said work-piece whereby said rollers are caused to travel over said 100 inner and outer joints respectively. 95

5. The process of forming a bellows member comprising the provision of annular sheet metal plates having flanges upon their inner and outer peripheries, assembling said 105 plates with the flanges of one plate in engagement respectively with corresponding flanges of adjacent plates thereby forming internal and external joints, supporting such assembly between soldering tools 110 engaging respectively said internal and external joints and causing relative rotation between said assembly and the solder-applying tool.

6. Means for applying solder to the inner 115 and outer joints of a hollow sectional metallic member comprising a soldering tool insertable within said member, a second soldering tool engageable with the exterior of said member, means for causing relative movement between said member and said tools whereby to apply solder simultaneously to the interior and exterior of the member and removable clamping means adapted to hold the sections in assembled 120 relation and in proper position relative to the said tools. 125

7. Means for applying solder to the inner and outer joints of a hollow sectional metallic member comprising a rotary soldering 130

tool insertable within said member, a second rotary soldering tool engageable with the exterior of said member, means for causing relative movement between said member and said tools whereby to apply solder simultaneously to the interior and exterior of the member and a removable clamp adapted to support the sectional member in proper position relative to the said tools and to permit rotation of said member.

In testimony whereof I affix my signature.

JOHN M. LEA.
